E. BÖNNELYCKE

Inventor

UNITED STATES PATENT OFFICE.

EMIL BÖNNELYCKE, OF WASHINGTON, DISTRICT OF COLUMBIA.

CHART.

Application filed January 25, 1922. Serial No. 531,728.

To all whom it may concern:

Be it known that I, EMIL BÖNNELYCKE, citizen of the United States of America, residing at 2123 California Street NW, 5 Washington, District of Columbia, have invented certain new and useful Improvements in Charts, of which the following is a specification.

This invention relates to a chart for indicating at a glance the particular ships assigned to sail, and those which have already sailed, from given ports, so that it will be unnecessary to resort to the use of the ordinary shipping schedules which are sometimes 10 incomplete and which contain information regarding ships in which the user of the chart has no interest.

More particularly the present invention resides in the provision of a chart having 20 thereon designated spaces to receive ship-identifying data showing the chronological order in which the identified ships are scheduled to depart, and designated spaces to receive ship identifying data showing the 25 chronological order in which ships have departed.

In some of its aspects, the invention also includes the provision of a geographically-indicated space to receive ship-identifying 30 data of departed ships without regard to the chronological order of departure of the ships.

The present invention embraces the use of movable buttons or pins for carrying 35 ship-identifying data, and preferably each button bears the name of the ship, the port to which it sails and the time required for the voyage. Thus, when the buttons are placed in the designated spaces for indicating the chronological order of departure, which spaces are preferably designated 40 according to the days of the month, the chart will show at a glance what ship or ships is or are scheduled to sail on any given day; and by adding the time indication on 45 the button, which is preferably given in days, to the sailing date, the date when the ship is due to reach its destination is obtained.

50 After a ship has sailed, its button is removed to one of the spaces designating the chronological order of departure of departed ships, so that it may be easily determined by means of the time indication on the button when the ship is due to arrive at the 55 port or ports indicated on the button.

If the chart contains, as in the preferred form, a geographically-indicated space to receive the ship-identifying buttons without regard to the chronological order of departure, then there are two identical buttons provided for each ship, one of which is placed in the "departed" space and the other of which is placed in the geographically-indicated space or map. Before the 60 ship has sailed, and while the button therefor is in the column designed to indicate the chronological order of departure, the other corresponding button may be stored in an alphabetically or otherwise designated space 65 to receive a supply of buttons.

In the preferred form, the space to indicate the chronological order of departure of the ships is sufficiently large to permit the buttons to be arranged thereon two months 70 in advance, so that at all times the future sailings can be easily noted, and so that as the end of the month approaches, the sailings during the next month will be shown. In practice, it is considered advisable to rearrange monthly the buttons in the spaces 75 for indicating the chronological order of departure. These spaces are divided into two parts, one of which is designated "Present month" and the other of which is designated 80 "next month."

In order that the schedule of sailings and the intended arrivals of ships from foreign ports may be readily seen, the preferred 85 form of the chart comprises two substantially identical parts each as above described, one for eastbound ships and the other for westbound ships; and hence, in the preferred form, the geographically-indicated space to receive the ship-identifying buttons 90 without regard to chronological order of departure is divided into two parts, designated 95 "Eastbound" and "Westbound."

Other features and advantages will hereinafter appear.

In the accompanying drawings:

Figure 1 shows the chart of the present invention in its preferred form.

Fig. 2 shows a pair of buttons carrying ship-identifying data.

Fig. 3 is an edge view of one of the buttons.

Fig. 4 is an enlarged fragmentary view of a portion of Fig. 1.

The chart of the present invention may 110 be printed, photolithographed or otherwise marked or indicated upon a sheet A. The

designated spaces B to receive ship-identifying data of ships scheduled to depart are formed by ruled lines 10; and each space is provided with a numeral 11 to indicate 5 the date of the month. The chart also comprises designated spaces C for receiving ship-identifying data of departed ships. These spaces C are produced by ruled lines 12, and each space is provided with a numeral 13 indicating the day of the month; 10 the column of spaces C being provided with a caption "Departed" which indicates that ships identified under this column have sailed.

15 The chart further comprises a geographically-indicated space in the form of a map D. In the present case, the map D shows part of the Atlantic seaboard of the United States and the coast line of part of Canada 20 and Greenland on the one side, and on the other side it shows the coast line of a portion of Africa and Europe, and the British Isles. In other words, the map principally indicates the Atlantic Ocean, the chart being designed for use in connection with 25 trans-Atlantic shipping.

The present invention embraces the use of 30 movable pins or buttons 14, shown in Fig. 2; and each of these buttons bears the name 15 of the ship, its port or ports 16 of destination, and a time-indication 17 designating the 35 average length of time required for its voyage. These buttons 14 may be in any suitable form, but they are preferably provided, each, with a pin 18 (Fig. 3) to pierce the sheet A of the chart and to project into the backing of the chart should a backing be utilized.

Any suitable number of buttons may be 40 provided for each ship in which the user of the chart is interested; but in the preferred form there should be at least two identical buttons for each ship as above explained, one to be used in connection with the map D and 45 the other to be used in connection with the spaces B for ships scheduled to depart and spaces C for departed ships.

In practice, assisted by the schedules of sailings of the respective ships, the spaces B 50 designed to indicate the chronological sailing order of the ships are filled by placing in each space the proper button 14 for the ship scheduled to sail on the day indicated by that space. For example, as shown in 55 Fig. 4, the ship "America" is scheduled to sail on the 3rd of the month, and its button 14 is accordingly placed in the space B designated by the numeral "3." Since the "United States" also sails the same day, its 60 button is also placed in that space adjacent the "America" button. When a ship has sailed its button 14 is transferred from the space B to the particular space C in the departed column which is numbered to correspond to 65 the day on which the ship sailed. For in-

stance, as shown in the drawing, the "Paris," having sailed on the 2nd of the month, has its button transferred from the "2" space B to the "2" space C. It will then be apparent to the user of the chart that the 70 "Paris," having sailed on the 2nd of the month and requiring on the average seven days to make its voyage to Havre, will arrive on the 9th day of the month; and by inspecting the departed column the user may ascertain when any ship which has sailed at a certain time will reach its destination and what other ships sailing about the same time will reach the same port. 75

Simultaneously with the removal of the 80 button 14 to the departed column, its duplicate is taken from the column of alphabetically-arranged storage spaces E at the side of column C, and is placed on the map D so that it will have the appearance of being 85 upon the ocean. There will of course be at all times a number of ships en route to foreign ports, and the buttons corresponding to those ships will indicate at a glance their names and destinations with more ease than 90 would be possible by examining the buttons arranged in their chronological order of departure. When it has been determined by examination of the buttons on the map D that a certain ship has sailed, the corresponding button is sought in the departed column; and by adding to the number borne by the space in which the button is located the number on the button, the date upon 95 which the ship is likely to reach its port is ascertained. 100

When a ship reaches its destination, its button 14 is removed from the space C in the departed column to the alphabetically arranged storage column E; and, likewise, 105 its corresponding button 14 is removed to said storage column from the map D. This is preferably done daily, so that at all times the chart will only show the ships which are still en route or which are scheduled to sail. 110

As the end of the month approaches, it is desirable to ascertain information regarding ships sailing during the next month; and for this purpose there are provided spaces B' similar to the spaces B. These spaces B' 115 are provided with a caption 19 "Next month" while the spaces B are provided with a caption 20 "Present month." In practice, when the end of the present month is reached, all the buttons in the spaces B will have been 120 removed either to the departed spaces C or the map D, or through the departed spaces C and the map D to the alphabetically-arranged storage spaces E; or because of delays in sailings, or changes in schedule the 125 buttons will have been moved to the next-month spaces B'. The buttons in the next-month spaces B', which were arranged simultaneously with the buttons for the spaces B at the first of the previous month, are 130

transferred from the spaces B' to the spaces B, the next month having then become the present month. The next-month spaces B' having thus been vacated are filled by buttons corresponding to ships sailing the next month, or what is then the next month. This, of course, should be understood as being merely a suggestion as to the preferred mode of use of the chart. Obviously, other methods of arranging the buttons on the chart may be selected; for instance, the rearrangement of the chart may be effected on the 15th of the month. However, in practice it has been found advantageous to provide for an initial arrangement covering two months, so that all the spaces preceding the current spaces will be blank.

In contradistinction to the foregoing, it has been found in practice that for the departed spaces C it is merely necessary, and in fact is advantageous, to provide for a single month only; this being due to the fact that in trans-Atlantic shipping even the slowest ships do not require more than twenty days to reach their destinations, so that there would therefore always be from eight to twelve vacant spaces C between the buttons of ships which have sailed and are approaching their destination and those which have sailed on a current day.

It should be understood that the chart is designed to be altered day by day to the extent of transferring the buttons corresponding to ships which have sailed that day or the previous day from the spaces B to the departed spaces C, and of correspondingly transferring from the storage spaces E identical buttons to the map D. If this is done regularly, as is intended, the chart will at all times show what ships are in transit and what ships are scheduled to sail in the immediate future.

In its preferred form, the chart is designed to supply data for ships sailing both eastward and westward; and for this purpose additional chronologically-designated spaces B² and B³, similar to the spaces B and B', are provided to receive ship-identifying buttons 14 of ships which are scheduled to sail to sail from foreign ports to the home ports. The spaces B are provided with a caption 21 "Eastbound" and the spaces B² are provided with a caption 22 "Westbound." The departed spaces C are provided at the same side of the chart as the spaces B and adjacent thereto, and adjacent the spaces B² there are provided departed spaces C' to receive the ship-identifying buttons 14 from the spaces B² after the ship has sailed. In all respects, the spaces B and B' are similar to the spaces B² and B³, respectively; and in like manner, the spaces C' preferably correspond in all respects to the spaces C.

The map portion D is provided with a division line 23, and the space at one side of the division line is provided with a caption 24 "Eastbound" and the space at the other side is provided with a caption 25 "Westbound." When a ship is sailing eastward, the corresponding button 14 is placed at the side of the division line 22 bearing the "Eastbound" caption, and when a ship is sailing westward the corresponding button is placed at the side of the dividing line 75 bearing the "Westbound" caption.

Adjacent the departed spaces C' for westbound ships, there may also be provided alphabetically designated storage spaces E'.

Each of the designated spaces B, B', B² and B³, is preferably of such width as to accommodate at least five buttons 14, and the spaces C and C' may also have the same width, if desired.

In the operation of the chart in its preferred form the number of buttons required for each ship depends on how fast the ship is, that is on the number of round trips made by the ship during two months. A fast ship which for instance makes three round trips in two months would require at least seven buttons, namely three for the eastbound departure and departed spaces, three for the west-bound departure and departed spaces and one for the map space. A slower ship which only makes two round trips in two months would only require five buttons.

Variations and modifications may be resorted to within the scope of my invention and portions of the improvements may be used without others.

I claim as my invention:

1. The combination of a chart having thereon two separate sets of definite spaces which are numbered in counterpart to indicate the chronological order of ships' sailings, the first set indicating the ships scheduled to depart and the second set indicating departed ships; and a plurality of indicating devices, each bearing the name of a ship and its average time of voyage, adapted to be initially positioned in the spaces of the first set according to the chronological sailing schedule of the ships to which they relate, and to be successively transferred therefrom to the correspondingly-numbered spaces of the second set as said ships depart.

2. The combination of a chart having thereon two separate sets of definite spaces which are numbered in counterpart to indicate the chronological order of ships' sailings, the first set indicating the ships scheduled to depart and the second set indicating departed ships, and a geographically-indicated space; and two duplicate sets of indicating devices, each device bearing the name of a ship and its average time of voyage;

the indicating devices of one set adapted to be initially positioned in the first set of spaces according to the chronological sailing schedule of the ships to which they relate, 5 and to be successively transferred therefrom to the correspondingly-numbered spaces of the second set as said ships depart; the other

set of indicating devices adapted to be positioned in said geographically-indicated space simultaneously with the transfer of the 10 duplicate indicating devices of the first set from the first to the second set of spaces.

In testimony whereof I affix my signature.

EMIL BÖNNELYCKE.
